UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

PNEUMATIC HAMMER.

1,027,060.

Specification of Letters Patent. Patented May 21, 1912.

Application filed March 8, 1910. Serial No. 547,977.

To all whom it may concern:

Be it known that I, REINHOLD A. NORLING, a citizen of the United States, and a resident of Aurora, in the county of Kane 5 and State of Illinois, have invented certain new and useful Improvements in Pneumatic Hammers; and I do hereby declare that the following is a full, clear, and exact description thereof, reference being had to the accompanying drawings, and to the letters of reference marked thereon, which form a part of this specification.

This invention relates to a portable pneumatic tool or hammer of that class embracing a barrel or cylinder, a piston or plunger adapted to move therein, and a controlling valve through which the air or other fluid under pressure is admitted to and permitted to escape from the opposite ends of the cylinder or barrel to give reciprocatory movement to the plunger therein.

The invention is illustrated and described herein as applied to a riveting hammer, otherwise known as a long stroke hammer, 25 in which the movement of the piston or plunger is greater than its own length.

The invention consists of the combination of parts hereinafter described and more particularly pointed out in the appended 30 claims.

In the drawings:—Figure 1 is a longitudinal section through the hammer in a plane containing the axis of the barrel or cylinder and the axis of the throttle valve chamber. Fig. 2 is a similar section through the barrel on a plane through the axis thereof at an angle to the plane of the section of Fig. 1. Fig. 3 is a partial section through the barrel on an enlarged scale at still another angle to the plane of the section shown in Fig. 1. Fig. 4 is a partial longitudinal section through the axis of the barrel on a plane at a third angle to the plane of the section of Fig. 1. Figs. 5, 6, 7 and 8 represent longitudinal, axial sections of the barrel, the planes of said sections being the same, respectively, as those of Figs. 1, 2, 3 and 4. Fig. 9 is an end elevation of the inner end of the barrel indicating by the lines 1—1, 2—2, 3—3 and 4—4, the respective planes upon which the sections shown in Figs. 1 to 4, inclusive, and 5 to 8, inclusive, are respectively taken. Fig. 10 is a transverse section through Fig. 1 on the line 55 10—10 thereof. Fig. 11 is a similar trans-

verse section through Fig. 1 on the line 11—11 thereof. Fig. 12 is a third section through Fig. 1 on the line 12—12 thereof. Fig. 13 is an end elevation of the outer end of the valve block body. Fig. 14 is a longitudinal section through the axis of said valve block body on the line 14—14 of Fig. 13. Fig. 15 is a similar section on the line 15—15 of Fig. 13. Fig. 16 is a like section on the line 16—16 of Fig. 13. Fig. 17 is an end elevation of the inner end of said valve block body. Fig. 18 represents a transverse section through Fig. 14 on the line 18—18 thereof. Fig. 19 is a transverse section of Fig. 15 on the line 19—19 thereof. Fig. 20 is a transverse section through Fig. 16 on the line 20—20 thereof. Fig. 21 is an end elevation of the inner end of the valve block cap. Fig. 22 is a longitudinal axial section through said valve block cap on the line 22—22 of Fig. 21. Fig. 23 is a transverse section through Fig. 22 on the line 23—23 thereof. Fig. 24 is a longitudinal axial section through said valve block cap on the line 24—24 of Fig. 21. Fig. 25 is an end elevation of the outer end of said valve block cap. Fig. 26 is a longitudinal axial section through the controlling valve. Fig. 27 is a transverse section through the same on the line 27—27 of Fig. 26.

In that embodiment of my invention illustrated in the accompanying drawings, A represents the barrel or cylinder of the hammer; B, the piston or plunger adapted to reciprocate therein; C, the tool carrying spindle; and D, the tool, in this case a riveting head. The inner end of the cylinder A is externally screw-threaded, as at a, to receive the outer, internally screw-threaded end of a hollow head E. Said hollow head E is closed at its rear end, by an end wall E¹, and has formed integrally with it a handle F.

To insure a more rigid attachment of the head E to the cylinder, I provide the following construction: Said hollow head is split at its outer end and provided with a longitudinal recess e inclosed by laterally extending ears or lugs e¹, e¹. Said lugs are provided with openings through which extends a clamping bolt e² which is adapted to draw said ears together. The inner end of the main barrel is provided near its end with a series of longitudinally extending serrations a² and in said serrations engage

the serrated end of a block e^{30} which is located in the slot e (see Figs. 1 and 10) and which is held in rigid engagement with the serrations in said main barrel by means of a taper pin e^4 which is located in openings e^5 , e^6 in the ears or lugs e^1 and which engages in a hole or opening e^6 in the said block e^{30} . Said opening e^6 is arranged eccentrically with respect to the axis of the openings e^5 so that the taper pin engages between the opposite sides, respectively, of the opening e^6 and of the openings e^5 and wedges the block e^{30} against the barrel. Said taper pin is held in place by means of a nut e^7 between which and the outer surface of the adjacent ear or lug, there is interposed a spring washer e^8 to lock said taper pin in position.

The means for attaching the head to the cylinder or barrel just described forms no part of the present invention but has been made the subject-matter of a separate divisional application, filed May 9th, 1910, Serial No. 560,270.

G indicates a throttle valve chamber which is bored through the end wall E^1 of the head E , with its axis in a plane extending through the axis of said head parallel to the handle. One end of said throttle valve chamber is closed by an apertured collar g through which projects the end of the throttle valve stem G^1 , and the other end of said valve chamber is internally screwed threaded to receive a screw-threaded nipple G^2 to which the usual supply hose pipe (not shown) is connected. The inner end of said nipple is provided with an apertured ring g^1 which serves as a guide for the outer end of the valve stem G^1 . G^3 indicates the throttle valve and G^4 its seat against which it is held by means of a coiled spring g^2 which bears between the outer face of the valve and the inner face of the apertured ring g^1 .

G^5 indicates a hand-controlled lever or trigger pivoted at g^4 in a slot F^1 in the handle and having one end, G^6 , adapted to engage the projecting end of the throttle valve stem G^1 and the other end G^7 , in position to be grasped by the fingers when the handle of the tool is held by the operator.

50 The valve mechanism for controlling the admission and exhaust of air into and from the cylinder embraces a valve block H^x , provided with exhaust and admission ports and an annular or cylindric valve ring J surrounding said valve-block and arranged to slide endwise thereon to open and close said ports; said valve ring being provided with oppositely facing, differential pressure areas. Said valve block is located at the inner end of the barrel A and is made in two parts,—a body member H and a cap member I . Within the inner end of the valve block, that is to say, within the cap I , is located an auxiliary valve which controls the supply 65 of live air to the smaller pressure area of

the main valve and which has the form of a piston valve, embracing a sliding valve-piston N adapted to be operated by pressure of air compressed in the inner end of the cylinder in the backward stroke of the piston.

The valve-block body H rests at its forward end within an annular recess a^1 formed in the inner end of the piston barrel A . It is provided with a longitudinal bore, of substantially the diameter of that of the cylinder A and co-axial therewith. The cap member I is provided with a short annular projection I^1 which engages within the bore of said valve-block body, and rests at its rear end against the end wall E^1 of the plunger barrel. The valve block H^x is thus rigidly held in place between the inner end of the cylinder A and the end wall of the hollow head E .

The valve member J is in the form of a cylindric sleeve surrounding the valve-block H^x and arranged to have endwise sliding movement thereon. The valve block H^x is enlarged in diameter at its forward end to form an annular flange H^1 . The valve ring J is enlarged at its forward end to embrace said flange H^1 and is provided with an annular shoulder J^1 which is opposed to the rear face of the annular flange H^1 , and which forms the larger pressure area of the valve ring.

J^2 is an annular channel or groove formed in the inner surface of the valve ring J .

J^3 indicates a series of exhaust ports arranged circumferentially about the valve ring and opening through its walls. Said ports open into an exhaust space S surrounding the valve ring J and opening through ports S^1 to the outer air. The forward end of the valve-block cap I is made of larger diameter than the rear end of the valve-block body so as to form a forwardly facing, annular shoulder I^2 extending around the rear end of the said body, and the valve ring J is enlarged at its rear end, as indicated at J^4 , to embrace said valve-block cap.

J^5 indicates an annular shoulder on the inner surface of the valve ring J opposite the forwardly facing, annular shoulder I^2 of the cap. Said shoulder J^5 forms the smaller pressure area of the valve ring J . Within the inner enlarged end of the valve ring J is formed an annular groove or channel J^6 120 which is adapted to be brought into communication with the space between the shoulder J^5 and the shoulder I^2 on the valve block cap, when the valve ring has moved to the forward limit of its movement, as shown in Figs. 3 and 4. The forward movement of the valve J is limited by the inner end of the barrel A , while its rearward movement is limited by a shoulder I^4 formed on the cap I .

K indicates a set of longitudinal exhaust passages formed in the wall of the barrel A near its inner end and extending through the walls of the valve block to an annularly arranged series of exhaust ports K² which open through the outer surface of said valve-block near its rear end. Said passages K communicate with the interior of the barrel by means of ports K¹ near its inner end, 10 which ports are adapted to be closed by the piston when it nears the inner end of its return stroke (see Figs. 1, 5, 10 and 11). Said passages K and ports K¹ K² constitute the main exhaust passages or ports for the inner end of the cylinder and are adapted to permit the exhaust of the air from the inner end of the barrel, when the piston B is effecting its inward stroke, the main valve being then in such position that some of the 15 ports J³ thereof are in register with the ports K², as indicated in Fig. 1.

L L¹ (see Figs. 3, 4 and 10), indicate longitudinally extending passages formed in the walls of the barrel A and opening at 20 their forward ends into the barrel by means of ports l, l¹. The port l is located at a point which is adapted to be uncovered by the inner end of the plunger when the same approaches the outer limit of its stroke, 25 the port l¹ being located nearer the outer end of the cylinder than the port l. Said port l¹ is adapted to be uncovered by the rear end of the plunger on its return stroke. The passage L¹ is an auxiliary exhaust passage 30 for the escape of air from the outer end of the cylinder in the return stroke of the plunger, after said plunger has moved far enough from its forward end to uncover said port l¹. Said passage L¹ communicates at 35 its rear end with the exhaust space S surrounding the main valve, by means of a port l² which opens through the outer wall of the barrel at a point near the inner end of the latter. The passage L is a supply passage 40 adapted to supply air under pressure to the larger pressure area J¹ of the main valve for shifting the latter rearwardly. Said passage L extends a short distance into the wall of the valve block H and opens into the 45 space between the annular flange H¹ and the larger pressure area J¹ of said valve by means of a port L² extending through said annular flange H¹.

M indicates passages extending longitudinally through the walls of the main barrel or cylinder and which open into the interior of said barrel, at its outer end, through ports m (see Figs. 2 and 6) and which are adapted 50 for the exhaust of air from the outer end of the barrel during the outward stroke of the piston. Said passages extend through the walls of the valve block H (see Figs. 2 and 10) to points adjacent to and forward of the main exhaust ports K², where said passages open through the outer surface of the

valve block by means of ports M². The main exhaust ports K² are separated longitudinally from the ports M² by a distance equal to the total movement of the valve J, so that in the rearward position of said valve, certain of the ports J³ register with the ports K², and connect the exhaust space S with the inner end of the barrel, while in the forward position of said valve certain other of said ports J³ register with the ports M² and connect the outer end of the barrel with said exhaust space. 70

In the rear end of the valve block H are provided an annularly arranged series of radially extending ports R, which extend through the walls of said block and constitute the main supply ports for admitting air to the inner end of the cylinder. Said ports are adapted to be uncovered and brought into communication with the annular groove 80 or channel J⁰ of the valve ring J, for the admission of air to the inner end of the cylinder, when the valve J is in its forward position. 85

Passing now to a description of the valve-block cap I, the ports in said cap and the auxiliary valve located therein: Said cap is provided with a central bore I¹ forming a valve-chamber within which slides the valve-piston N. Said valve-chamber opens into 90 the cylinder at the forward face of the cap I and its forward part forms a rearward extension of the bore of the main cylinder. Said valve-piston has the form of a cylindrical shell or tube closed at its rear end and 100 open at its forward end and provided near its middle with an outwardly extending annular flange n. At the forward side of said flange the valve-shell is of larger diameter, as indicated at N¹, and said valve-shell is 105 of smaller diameter on the rear side of said flange, as indicated at N². A port N³ opens through the end wall E¹ from the throttle valve-chamber to the outer end of the bore of the cap I and acts upon the rear closed 110 end of the valve-piston, providing constant live air pressure against said rear end, constituting the smaller pressure area of said valve piston, whenever the throttle valve is open. The annular flange, n, is adapted to 115 engage a shoulder n¹ formed in the bore of the cap, which limits the forward movement of the auxiliary valve.

N⁴ indicates an apertured ring located 120 within the rear end of the bore of the cap between the end wall E¹ of the plunger cylinder and a shoulder n² formed on the inner surface of said bore. Said ring forms the rear part of the valve chamber, in which slides the rear end or smaller portion of the 125 valve piston.

The rear face of the cap I is provided with an annular recess P into which open ports p (see Fig. 1) which lead from the 130 throttle valve chamber. The cap is pro-

vided with an annularly arranged series of longitudinal passages P^1 opening from said annular recess P (Figs. 21 to 24) and extending nearly to the forward end of said cap where they turn outwardly at right angles and open by ports P^2 through the outer annular surface of said cap into the annular space formed by the channel J^6 of the valve ring J . The said ports P^2 , two of which are preferably provided for each passage P^1 , (Fig. 23) are in position to be in communication with said annular space, constantly, or in all positions of the valve ring J . Some of said passages P^1 , four out of the eight shown in the drawings, are connected by means of radially arranged ports P^y with the central valve chamber in the said cap; said ports P^y extending inwardly from the passages P^1 and opening 20 at their inner ends into the valve chamber near the forward end of the same. Said cap is also provided with a small number of radially arranged ports P^3 , P^4 , preferably two in number and arranged diametrically opposite each other in the cap, which open at their outer ends through the marginal part or shoulder I^2 of the cap and at their inner ends into the auxiliary valve chamber near its forward end. The said 25 ports P^3 P^4 are shown as consisting of two straight ports arranged in angular relation to the central axis of the cap. The outer ends of said ports P^3 open into the space between the said shoulder I^2 and the smaller pressure area J^5 of the valve ring J , and serve to supply live air to effect the forward movement of the valve. The inner ends of said ports P^3 in common with the inner ends of the ports P^y , are so located in the 30 auxiliary valve chamber as to be uncovered by the rear end of the piston N of the auxiliary valve, when said piston is in its rearward or retracted position, as seen in Fig. 1, and to be covered or closed by said piston 35 when the latter is thrown to its forward position, as seen in Fig. 2. When said valve piston is retracted, a part of the air passing inwardly to the auxiliary valve chamber from the passages P^1 through the ports P^y , 40 passes outwardly from said valve chamber through the ports P^3 , for actuating the main valve.

One of the passages P^1 in the valve block cap opens by means of a port P^6 (see Fig. 55) through the forward face of the cap, and in line with this is formed a longitudinal passage Q in the valve block body H , which extends to the annular flange H^1 , and is there provided with a small leak port Q^1 , 60 adapted to supply continuously a small quantity of live air to act on the larger pressure area J^1 of the valve J (see Fig. 3). Said passage Q also opens through the outer surface of the valve block by a port 65 Q^2 (see Fig. 16) which is adapted, when

the main valve is in its rearward position, to communicate with the annular channel J^2 formed in the inner surface of said valve. One of the exhaust passages M , which leads to the outer end of the cylinder is provided with a port Q^3 (see Fig. 2) located a short distance forward of the port M^2 of said passage M . Said channel J^2 , when the valve ring is in its rearward position, stands opposite the port Q^3 , and serves to establish communication, through said port Q^3 and the port Q^2 , between the passage Q and said exhaust passage M for the supply of air to the outer end of the cylinder to effect the inward movement of the plunger.

The operation of the valve mechanism is as follows:—Starting with the parts in the position indicated in Fig. 1, with the plunger at the inner end of its stroke, and the main valve ring J and the auxiliary valve piston N at their rearward limits of movement, the inner ends of the ports P^2 and P^y , in the valve block, are at this time uncovered by the auxiliary valve piston, the main supply ports R and the exhaust ports M^2 are closed, the exhaust ports H^2 are open and the groove J^2 is in register with the ports Q^2 and Q^3 . The opening of the throttle valve admits live air to the recess P , at the inner end of the cap I , from which a small amount passes through some of the passages P^1 and the ports P^y to the auxiliary valve chamber, and thence to the inner end of the cylinder and also from the said valve chamber through the radial ports P^3 to the smaller pressure area J^5 of the main valve J . This small amount of air gives the piston B its initial movement and also causes the valve ring to shift to its forward position, as may be seen in Fig. 3. This movement of the valve ring J uncovers the radially extending supply ports R , at the inner end of the valve block H , and connects them through the channel J^6 , and all of the passages P^1 and their ports P^2 with the recess P , thereby admitting a large supply of live air to the inner end of the cylinder to drive the piston with force outwardly to make its working or power stroke. This movement of the valve also brings the ports J^2 of the valve ring into register with the exhaust ports M^2 in the valve block and thus connects the exhaust passages M leading from the outer end of the cylinder with the exhaust space S , (Fig. 3) permitting exhaust from the outer end of the cylinder as the plunger moves outwardly. When nearing the outer end of its stroke, the piston uncovers the port l which permits live air from the inner end of the cylinder to pass through the passage L and port L^2 to the larger pressure area J^1 of the valve ring J , which causes said valve to shift to its rearward position against the live air pressure on its smaller pressure area J^5 . This move- 125 130

ment of the valve ring J closes the admission ports R , at the inner end of the valve block H , and thereby cuts off the supply of live air to the inner end of the cylinder except for the comparatively small amount admitted by the ports and passages P^y , P^z . Said movement of the valve ring also covers the ports M^2 and brings the ports J^2 into register with the ports K^2 , thus connecting the exhaust space S , through the passages K and the ports K^1 for the exhaust of air from the inner end of the barrel. The small amount of air admitted by the ports and passages P^y , P^z thus escapes through the ports K^1 . There being now no pressure on the forward, larger pressure area of the auxiliary valve piston N , the constant live air pressure on its rear smaller area moves said valve piston to its forward position (see Fig. 4) when its forward part N^1 covers both sets of ports P^y , P^z , thereby cutting off all supply of live air to the inner end of the cylinder, and also to the smaller pressure area J^s of the main valve-ring. In the movement of the main valve to its rearward position, the channel J^2 is brought opposite the port which opens into the live air passage Q , in the valve block, thereby establishing connection through said channel, between said port Q^2 and the port Q^3 , and admitting live air through the said port Q^3 , to one of the exhaust passages M , with which the port Q^3 connects, and its port m , at the rear end of the cylinder, to drive the piston toward the inner end of the cylinder in the backward or return stroke. When the piston on its return stroke reaches and covers the main exhaust ports K^1 , the exhaust from the inner end of the cylinder is cut off and the air contained between the inner end of the piston and the valve block cap is compressed by the continuous inward advance of the piston due to its momentum. The force of this compressed air is brought to bear against the forward larger pressure area of the auxiliary valve piston N which causes it to move to its rearmost position against the pressure of the live air against its smaller area. This uncovers the ports P^y and P^z to admit live air to the inner end of the cylinder and to the smaller pressure area of the valve J , and the operation is continued as before. To prevent any accumulation of air in the space between the radially extending smaller flange n of the auxiliary valve and the annular shoulder n^1 in the cap I , a leak port P^a is provided (see Figs. 1 and 24) said port opening through the outer surface of the cap to the exhaust space S . A small leak port P^s connects one of the angular ports P^z (see Fig. 1) with the inner end of the cylinder to allow the escape of any live air which may leak from the channel J^s to the smaller pressure area J^s of the valve J , and cause said valve to

shift rearwardly at the wrong time. The leak passage Q^1 , above described, connecting the live air passage Q with the larger area J^1 of the valve J , admits a small quantity of live air at this point which tends to move said valve to its rearward position, which is its desirable position in starting the tool.

It will be seen from this description that the main controlling valve of my improved hammer is a valve of differential area in which the pressure on both areas of the valve is intermittent, neither pressure being a constant one, and that at one instant only, namely, at the time when it is shifted from its outermost to its innermost position, is pressure exerted on both ends of the valve. The intermittent supply of air to the opposite ends of said main valve is controlled by means of the auxiliary valve and the piston. The auxiliary valve is also a differential area valve but its smaller pressure area is subjected to constant live air pressure, while its larger pressure area is subjected to an intermittent pressure under the compressive action of the piston on the air in the inner end of the cylinder when the piston approaches the inner end of its return stroke.

It is to be noted that when the piston is making its return stroke, after it passes the port I^1 , the outer end of the cylinder is opened to the exhaust space S through the exhaust passage L^1 , and the exhaust port L^2 . The live air supplied to the outer end of the piston thus only acts for a short time to give it an initial movement, its further movement to the inner end of the cylinder being due to its momentum. This greatly reduces the shock against the rear end of the hammer, which is further reduced by the cushioning action of the air compressed at the end of said stroke.

I claim as my invention:

1. The combination with a cylinder and a plunger therein, of a live air actuated controlling valve and an auxiliary valve operated by air compressed in the inner end of the cylinder in the backward stroke of the plunger, for controlling the admission of live air for actuating said controlling valve, and means controlled by said auxiliary valve for admitting a small amount of air to the inner end of the cylinder simultaneously with the admission of air to actuate the controlling valve.

2. The combination with a cylinder and a reciprocating plunger therein, of a controlling valve for controlling the admission and exhaust of air into and from the cylinder, embracing a valve co-axial with said cylinder and having oppositely facing, differential pressure areas, means controlled by the plunger for admitting live air to the larger pressure area of said valve, an auxiliary valve controlling the admission of live air

- to the smaller pressure area of said main valve, said auxiliary valve being operated by pressure of air compressed in the inner end of the cylinder in the backward stroke of the plunger, and means controlled by said auxiliary valve for admitting a small amount of live air to the inner end of the cylinder simultaneously with the admission of live air to the smaller pressure area of said main valve.
3. The combination with a cylinder and a reciprocating plunger therein, of a controlling valve for controlling the admission and exhaust of air into and from the cylinder, embracing a valve co-axial with said cylinder and having oppositely facing, differential pressure areas, means controlled by the plunger for admitting live air to the larger pressure area of said valve, and an auxiliary valve co-axial with said main valve controlling the admission of live air to the smaller pressure area of said main valve, said auxiliary valve being operated by pressure of air compressed in the inner end of the cylinder in the backward stroke of the plunger, and means controlled by said auxiliary valve for admitting a small amount of live air to the inner end of the cylinder simultaneously with the admission of live air to the smaller pressure area of said main valve.
4. The combination with a cylinder and a reciprocating plunger therein, of a controlling valve for controlling the admission and exhaust of air into and from the cylinder, embracing an annular valve co-axial with said cylinder having oppositely facing, differential pressure areas, means controlled by the plunger for admitting live air to the larger pressure area of said valve, an auxiliary valve co-axial with and located within said main valve adapted to control the admission of live air to the smaller pressure area of said main valve, said auxiliary valve being operated by the pressure of air in the inner end of the cylinder in the backward stroke of the plunger and means controlled by said auxiliary valve for admitting a small amount of air to the inner end of the cylinder simultaneously with the admission of air to actuate the controlling valve.
5. The combination of a cylinder provided at its inner end with an auxiliary valve chamber opening into and forming an end-wise extension of the bore of said cylinder, a reciprocating plunger in said cylinder, a main controlling valve having oppositely facing, differential pressure areas, means controlled by the plunger for admitting live air to the larger pressure area of said valve, and a valve piston arranged to slide in said auxiliary valve chamber for controlling the admission of live air to the smaller pressure area of said main controlling valve, said valve piston having a larger pressure area subject to the action of air compressed by the plunger in the inner end of the cylinder, and a smaller pressure area subject to constant live air pressure.
6. The combination with a cylinder and a reciprocating plunger therein, of a controlling valve for controlling the admission and exhaust of air into and from the cylinder, embracing a valve block located at the inner end of said cylinder provided with a set of admission ports and two sets of exhaust ports, and a hollow valve surrounding said valve block and adapted to slide thereon to control the admission and exhaust of air through the ports in said valve block, said hollow valve having oppositely facing differential pressure areas, means controlled by the plunger for admitting live air to the larger pressure area of said valve, and an auxiliary valve co-axial with said valve block controlling the admission of live air to the smaller pressure area of said main valve, said auxiliary valve being operated by pressure of air compressed in the inner end of the cylinder in the backward stroke of the plunger.
7. The combination with a cylinder and a reciprocating plunger therein, of a controlling valve for controlling the admission and exhaust of air into and from the cylinder, embracing a valve block located at the inner end of said cylinder provided with a set of admission ports and two sets of exhaust ports, and a hollow valve surrounding said valve block and adapted to slide thereon to control the admission and exhaust of air through the ports in said valve block, said hollow valve having oppositely facing, differential pressure areas, means controlled by the plunger for admitting live air to the larger pressure area of said valve, and an auxiliary valve located within said valve block controlling the admission of live air to the smaller pressure area of said main valve, said auxiliary valve being operated by pressure of air compressed in the inner end of the cylinder in the backward stroke of the plunger.
8. The combination with a cylinder and a reciprocating plunger therein, of a controlling valve for controlling the admission and exhaust of air into and from the cylinder embracing a valve block located at the inner end of the cylinder provided with a central bore co-axial with that of the cylinder, and an annular valve adapted to slide on said valve block, said annular valve having oppositely facing, differential pressure areas, said valve block being provided with two sets of exhaust ports and a set of admission ports, means controlled by the plunger for admitting live air to the larger pressure area of said valve, and an auxiliary valve for controlling the admission of live air to the smaller pressure area of said main valve.

- valve, said auxiliary valve being operated by the pressure of air compressed in the inner end of the cylinder in the backward stroke of the plunger.
5. 9. The combination with a cylinder and a reciprocating plunger therein, of a controlling valve for controlling the admission and exhaust of air into and from the cylinder, embracing a valve block located at the inner 10 end of the cylinder provided with a central bore co-axial with that of the cylinder, and an annular valve adapted to slide on said valve block, said annular valve having oppositely facing, differential pressure areas, and said valve block being provided with 15 two sets of exhaust ports and a set of admission ports, means controlled by the plunger for admitting live air to the larger pressure area of said valve, and an auxiliary valve for controlling the admission of live 20 air to the smaller pressure area of said main valve, said auxiliary valve being co-axial with and located within the inner end of said valve and being operated by the 25 pressure of air compressed in the inner end of the cylinder in the backward stroke of the plunger.
10. The combination with a cylinder and a reciprocating plunger therein, of a controlling valve for controlling the admission and exhaust of air into and from the cylinder, embracing a valve block located at the inner end of the cylinder provided with a central bore co-axial with that of the cylinder, and an annular valve adapted to slide on said valve block, said annular valve having oppositely facing, differential pressure areas, and said valve block being provided with two sets of exhaust ports and a 30 set of admission ports, means controlled by the plunger for admitting live air to the larger pressure area of said valve, and an auxiliary valve for controlling the admission of live air to the smaller pressure area of said main valve, said auxiliary valve being operated by the pressure of air compressed in the inner end of the cylinder in the backward stroke of the plunger.
35. 11. The combination with a cylinder and a reciprocating plunger therein, of a controlling valve for controlling the admission and exhaust of air into and from the cylinder, embracing a valve block located at the inner end of the cylinder provided with a central bore, and an annular valve adapted to slide on said valve block having oppositely facing, differential pressure areas, said valve block being provided with two sets of exhaust ports and a 40 set of admission ports, means controlled by the plunger for admitting live air to the larger pressure area of said valve, and an auxiliary valve for controlling the admission of live air to the smaller pressure area of said main valve, said auxiliary valve being operated by the pressure of air compressed in the inner end of the cylinder in the backward stroke of the plunger, and means controlled by said auxiliary valve for admitting live air simultaneously to the inner end of the cylinder and to the smaller pressure area of said annular valve.
45. 12. A valve embracing a valve block provided with a valve chamber and two sets of ports opening at their inner ends into said chamber, one set of said ports constituting admission ports adapted to supply air to said chamber, and the other set constituting 70 exit ports adapted to supply air from said chamber to a space exterior to said valve block, and a valve piston adapted to simultaneously open the inner ends of both sets of ports and to simultaneously close the inner ends of both sets of ports.
50. 13. A valve embracing a valve block provided with a valve chamber, a plurality of longitudinally extending supply passages in said valve block provided with exit ports 75 in the outer surface of said valve block, a set of ports connecting said passages with said valve chamber a set of exit ports adapted to supply air from said valve chamber to a space exterior to said valve block, each 80 of said ports being located between two of said longitudinally extending passages which are adjacent to each other, and a valve piston adapted to simultaneously open and close the inner ends of both sets 85 of ports opening into said valve chamber.
55. 14. The combination with a cylinder and a reciprocating plunger therein, of a controlling valve for controlling the admission and exhaust of air into and from the cylinder, embracing a valve block located at the inner end of the cylinder provided with a central bore, and an annular valve adapted to slide on said valve block having oppositely facing, differential pressure areas, said valve block 100 and valve being provided with two sets of exhaust ports and said valve block having a plurality of radially extending admission ports, means controlled by the plunger for admitting live air to the larger pressure area of said valve, a cap forming the end of said valve block provided with an inner chamber, a plurality of live air passages in said cap opening through ports in the outer surface of said cap, said annular valve being constructed to open said ports to said radially extending ports when in its outer position, ports connecting some of said supply passages with the chamber in said cap, ports leading from said chamber to the 105 smaller pressure area of said main valve, and an auxiliary valve located in and adapted to slide in said chamber in the cap and being operated by the pressure of air compressed in the inner end of the cylinder in 110 the backward stroke of the plunger.
60. 15. In combination with a cylinder provided with an exterior bearing surface, a valve ring adapted to slide thereon, laterally separated, longitudinal passages pro- 115
65. 16. A valve embracing a valve block provided with a valve chamber and two sets of ports opening at their inner ends into said chamber, one set of said ports constituting admission ports adapted to supply air to said chamber, and the other set constituting 120 exit ports adapted to supply air from said chamber to a space exterior to said valve block, and a valve piston adapted to simultaneously open the inner ends of both sets of ports and to simultaneously close the inner ends of both sets of ports.

vided with ports opening through said bearing surface, and said valve ring being provided with a circumferentially extending channel on its bearing surface adapted to 5 connect said ports.

16. In combination with a cylinder and a reciprocating plunger therein, a main controlling valve comprising a bearing member formed at the inner end of the cylinder and a 10 valve ring adapted to slide thereon, a longitudinally extending exhaust passage for the outer end of the cylinder, said exhaust passage being provided at its inner end with two longitudinally separated ports, an exhaust 15 port and a supply port, opening through the bearing surface of said valve bearing member, a longitudinal supply passage laterally separated from said exhaust passage extending through said valve bearing member 20 and provided with a port opening through the bearing surface thereof, and said valve ring being provided with a circumferentially extending channel adapted to connect said supply port of the exhaust passage with 25 the port connected to said supply passages, when said valve ring is shifted to close said exhaust port.

17. In combination with a cylinder and a reciprocating plunger therein, a main controlling valve embracing a valve block member and a valve ring member adapted to slide thereon, said valve ring member having oppositely facing differential pressure areas and said valve block member having 35 shoulders of different area opposing the pressure areas of said valve ring, a circumferentially extending channel in said valve ring located at the rear of the smaller pressure area of said valve ring member, a plu-

rality of live air ports in said valve block 40 member at the rear of the said shoulder of smaller area for the constant supply of live air to said channel, a plurality of radially extending admission ports located forward of said shoulder of smaller area, and said 45 valve ring being constructed to open a passage about said last named shoulder to connect said live air ports with said admission ports when at its forward position and to close said passage when in its retracted position. 50

18. In combination with a cylinder and a reciprocating plunger therein, a main controlling valve embracing a bearing member formed at the inner end of the cylinder and a valve ring adapted to slide thereon, two sets of exhaust ports opening through the bearing surface of said bearing member, a set for the exhaust from the inner end of the cylinder and a set for the exhaust from 60 the outer end of the cylinder, each set being located in a plane longitudinally separated from the plane of the other set, and the valve ring being provided with two sets of ports all arranged in the same plane, 65 one set of said ports in the valve ring registering with one set of exhaust ports in one position of the valve ring and the other set registering with the second set of exhaust ports in the other position of said valve ring. 70

In testimony that I claim the foregoing as my invention I affix my signature in the presence of two witnesses, this 25th day of February A. D. 1910.

REINHOLD A. NORLING.
